Primary Examiner — Prabhakar Deshmukh

(74) *Attorney, Agent, or Firm* — Mark D. Trenner; Trenner Law Firm, LLC

(57) **CLAIM**

The ornamental design for a bowling warm-up and training device, as shown and described.

DESCRIPTION

FIG. 1 is a perspective view of a bowling warm-up and training device showing my new design;

FIG. 2 is a front elevation view thereof, the rear elevation view being a mirror image thereof;

FIG. 3 is a left side elevation view thereof, the right side elevation view being a mirror image thereof;

FIG. 4 is a top plan view thereof; and,

FIG. 5 is a bottom plan view thereof.

1 Claim, 3 Drawing Sheets
